[57] CLAIM

The ornamental design for a container for cosmetic products, as shown and described.

DESCRIPTION

FIG. 1 is a front elevational view of a container for cosmetic products, showing my new design, the side opposite that shown in FIG. 1 being identical thereto except as to the region of the two small circles at the top of FIG. 1, the appearance of which in rear elevation is apparent from FIG. 2;

FIG. 2 is a side elevational view thereof taken from the left of FIG. 1, the side opposite that shown in FIG. 2 being the mirror image thereof;

FIG. 3 is a top plan view thereof; and,

FIG. 4 is a bottom plan view thereof.
